UNITED STATES PATENT OFFICE.

KEPPEL DISNEY, OF VANCOUVER, BRITISH COLUMBIA, CANADA.

STORAGE BUILDING FOR MOTOR CARS AND THE LIKE.

Application filed June 12, 1926. Serial No. 115,693.

My invention relates to improvements in storage buildings for motor cars and the like the objects of which are to utilize the greatest amount of floor space and to provide for 5 expeditious handling of cars between one floor and another.

The invention consists essentially of a building having a plurality of superimposed floors along which aisles are provided 10 having storage spaces communicating therewith, such aisles being at a lower level than that of the storage spaces and provided with trackage adapted to accommodate an electric tramway for the purpose of conveying 15 the cars from their storage places to an elevator communicating with the several floors. A further object is to provide means whereby the conductors or trolley wires of each floor, which serve to convey the current 20 required for the running of the tramway, are only in circuit with the current supply at the time when the tramway and the elevator on which it is carried are in register with the floor, as will be more fully de- 25 scribed in the following specification, in which:

Fig. 1 is a plan view of a typical floor of a two elevator unit form of the building.

Fig. 2 is a plan view of a single elevator 30 unit form of the building.

Fig. 3 is an enlarged sectional view taken on the line 3—3 of Figure 1.

Fig. 4 is an enlarged sectional view showing the tramway delivering cars to the 35 storage spaces.

Fig. 5 is a detailed view showing the manner in which electrical connection is made between the trolley rails of the elevator car and the corresponding rails in one 40 of the aisles.

In the drawings like characters of reference indicate corresponding parts in each figure.

The numeral 1 indicates the outside walls 45 of the building. The numeral 2 indicates generally a floor which is divided into a central or transverse space forming an aisle 3 and 4 indicates a plurality of storage spaces. A well opening indicated by the 50 numeral 5 is provided in each of the aisle spaces in any suitable position for the purpose of accommodating one or more elevators 6 by which communication is established between the different floors. The 55 aisles 3 are set to a lower level than the main portions or storage spaces 4, see Fig-

ures 3 and 4. Lengthwise of each aisle the tramway tracks 7 are laid extending to the outside wall and coming to an abrupt end at the well openings 5. Suitably carried from the ceilings 8 above the aisles 3 are properly insulated electrical conductors or trolley wires 9, which wires terminate at the wells in a shoe 10, see Figure 5, each having an upstanding member 11 extending somewhat into the well opening and forming a terminal member against which contact is adapted to be made from the feeders hereinafter referred to. The elevator 6 is of any suitable type and is adapted for 70 vertical movement between a pair of guides 12, behind one of which the car counterweight 13 and hoisting ropes are adapted to be accommodated, so that relatively little space is lost to car storage.

The numeral 14 indicates the elevator control switch which is set on one of the frame members of the elevator car frame 15 so as to leave the entire elevator floor space free from obstruction.

The numeral 16 indicates an electric tram having tracks wheels 17 which are motor driven in any suitable manner, the operation of the tram being controlled by a switch 18 mounted upon a standard 19. A 85 trolley arm 20 is springingly supported from the upper extremity of the standard 17 and is adapted to form a running connection with the trolley wires 9 and the feeders 21 which are carried by, and insulated from, 90 the elevator car frame 15. These feeders are connected with a constant source of electrical energy by a pair of cables 22 extending between the elevator and the power lines of the building. At opposite ends of the 95 feeders are pairs of trigger contacts generally indicated by the numeral 23 and which are each formed with a base member 24 having a pair of jaws 25 at its outer end supporting a pin 26 which forms a fulcrum for a bell crank 27. The inner leg 28 of the bell crank is normally held in raised position by a spring 29 and is limited in its movement by its projection through a slotted standard 30. The outer leg 31 of the bell 100 crank 27 is rearwardly curved at its outer ends so that it may move into easy engagement with the upstanding member 11 of the shoe 10 as the elevator comes to rest at its appointed floor. By this means an electrical contact is formed between the feeders 21 and the trolley wires of a given floor in such 105 110

a manner as to enable the tram to be run to and from the elevator and along the aisles.

It will also be noted that except at such moments as the elevator platform is passing

5 a floor or when the elevator platform is at rest at a floor, no current is flowing through the trolley wires 9.

I may prefer to provide a magnetically operated contact between the feeders and

10 the trolley wires, whereby no contact is made until the elevator car comes to rest at a floor, so that no temporary current flow can enter the trolley wires of a floor until the car stops at that floor.

15 Having thus described the several parts of my invention I will now briefly explain its use.

A car entering the ground floor from the street is run onto the tram 16 upon the plat-

20 form of an elevator 6. The elevator is then raised to the floor upon which the car is to be stored. As the elevator comes to rest at its appointed floor, automatic contact is made by the trigger contacts 23 and the

25 shoes 10 of the trolley wires 9, thus permitting the said wires to be energized from the power cable 22 carried by the elevator 6. The tram is run from the elevator along

30 the aisle 3 until the car to be stored is brought opposite its appointed place in one of the storage spaces 4, when it is driven or pushed off the tram into its stall. In a reverse manner cars are taken from their storage onto the tram and conveyed to the

35 elevator and from thence are lowered to the ground floor where they are driven off.

It will thus be seen that by my method of car handling no space is required in the aisles, wherein the cars are required to pass

40 or turn, so that the aisles may be of considerably less width, and the cars can be parked closer together than is possible in storage buildings of present construction and arrangement.

45 What I claim as my invention is:

1. A storage building for motor cars and the like comprising two or more superimposed floors and an elevator communicating between the floors, an aisle extending from

the elevator shaft bounded on one or both 50 sides with car storage spaces, electric conductors extending along the aisle, energized feeders carried by the elevator and an electric tram adapted to be carried by the elevator for transporting a car along the aisle, 55 said tram deriving its energy from the feeders and the conductors.

2. A storage building for motor cars and the like comprising two or more superimposed floors and an elevator communicating 60 between the floors, an aisle extending from the elevator shaft bounded on one or both sides with car storage spaces, electric conductors extending along the aisle, said conductors being normally unenergized, energized feeders carried by the elevator, means as the elevator comes to rest at a floor for establishing an electrical connection between the feeders and the conductors of the adjoining aisle, and a tram adapted to be carried by the elevator and deriving its energy from the feeders and the conductors for transporting a car along the aisle.

3. A storage building for motor cars and the like comprising two or more superimposed floors and an elevator communicating between the floors, an aisle extending from the elevator shaft bounded on one or both sides with car storage spaces, electric conductors extending along the aisle, said conductors being normally unenergized, energized feeders carried by the elevator, means as the elevator comes to rest at a floor for establishing an electrical connection between the feeders and the conductors of the adjoining aisle, and a tram adapted to be carried by the elevator and deriving its energy from the feeders and the conductors for transporting a car along the aisle, 70 trigger member at the ends of the feeders adapted to move into engagement with corresponding contact members upon the conductors as the elevator comes into register with the floor of an aisle.

Dated at Vancouver, B. C., this 26th day of May, 1926.

KEPPEL DISNEY.
